COMBINED SCALE STAND, PENCIL TRAY, AND BAG HOLDER

Edwin F. Schild, Schiller Park, Ill.

Application May 28, 1954, Serial No. 30,733

Term of patent 14 years

(Cl. D80—9)

Fig. 1.

Fig. 2.

Fig. 3.

Fig. 4.

Fig. 1 is a top plan view of a combined scale stand, pencil tray and bag holder embodying my new design;

Fig. 2 is a front elevational view;

Fig. 3 is a side elevational view, and

Fig. 4 is a perspective view of the same.

I claim:

The ornamental design for a combined scale stand, pencil tray and bag holder, substantially as shown.
